UNITED STATES PATENT OFFICE

1,935,556

FEEDING MECHANISM FOR SEWING MACHINES

Horace F. Gruman, St. Louis, Mo., assignor to Lewis Invisible Stitch Machine Company, St. Louis, Mo., a corporation of Maine

Original application January 31, 1931, Serial No. 512,661. Divided and this application October 7, 1931. Serial No. 567,487

1 Claim. (Cl. 112—215)

This invention relates to new and useful improvements in feeding mechanisms for sewing machines and constitutes a division of my co-pending application Serial No. 512,661, filed Jan. 5, 1931, for improvements in sewing machines.

Among the several objects of this invention are to provide a 4-motion feeding mechanism adapted particularly to intermittently feed down-turned edge portions of fabrics past a stitch forming mechanism; to provide a vertically disposed feed dog for cooperation with a vertically disposed presser foot and means for imparting backward and forward movements to the feed dog and lateral back and forth movements thereto; to provide such a mechanism which can be readily placed within a tubular work arm of comparatively small cross sectional area, and to provide such a feeding mechanism which is composed of comparatively few parts and is therefore simple in operation and cheap to manufacture.

With these and other objects in view which will more fully appear, the nature of the invention will be more clearly understood by following the description, the appended claim, and the several views illustrated in the accompanying drawings.

In the drawings:—

Figure 1 is a top plan view showing the application of my invention to the work arm of a sewing machine of the feed-off-the-arm type,

Figure 2 is a vertical longitudinal sectional view through the work arm,

Figure 3 is a detail sectional view of the cam means for imparting the lateral back and forth movements to the feed dog,

Figure 4 is a vertical cross sectional view taken on the line 4—4 of Figure 1,

Figure 5 is a perspective view of the bearing block on which the front end of the feed bar is slidably mounted,

Figure 6 is a perspective view of the feed dog,

Figure 7 is a perspective view of the work guide with which the feed dog cooperates, and

Figure 8 is a perspective view of the presser foot which cooperates with the feed dog and work guide.

Like reference numerals designate corresponding parts throughout the several figures of the drawings.

Referring to the drawings, I have shown my invention applied to a tubular work arm 5 of a sewing machine of the feed-off-the-arm type. Removably mounted within the work arm 5 is a bracket 6 having a front bearing 7, a rear bearing 8, intermediate bearing 9, and a post 10 located 55 in rear of the bearing 8. Journalled in the bear-

ings 7, 8 and 9 is a needle shaft 11 which is oscillated from a rock shaft 12 through the medium of a rock arm 13 fixed to the shaft 12, a rock arm 14 fixed to the needle shaft 11, and a link 15 which connects the rock arms 13 and 14. Fixed 60 to the post 10 is a transverse pivot pin 16 and journalled on this pin is a feed rocker or lever 17. A feed bar 18 extends longitudinally of the work arm 5 and the rear end of this bar is pivotally connected by a ball joint 19 to a pivot bolt 65 20 mounted in the upper end of the lever 17. The front end of the feed bar 18 is provided with a laterally extending fork 21 whose arms 22, 22 are disposed above and below the needle shaft 11. A slide block 23 is freely mounted on the 70 needle shaft and is located between the arms 22, 22 of said fork for sliding contact therewith. The free end of the fork is closed by a cam plate or follower 24 which projects forwardly therefrom for constant engagement with a peripheral 75 cam 25 fixed on the needle shaft 11. A coil spring 26 is disposed between the feed bar 18 and the slide block 23 and serves to yieldably retain the cam plate or follower 24 in constant engagement with the cam 25. A tongue or rib 27 integral 80 with the bracket 6 in the work arm 5 and extending longitudinally thereof, cooperates with a groove 28 formed in the lower part of the slide block 23 and retains the latter against axial 85 movements about the needle shaft 11.

A vertical feed dog 29 is detachably secured to the feed bar 18 by screws 30. This feed dog has its feeding portions 31, 31 projecting into slots 32, 32 in a vertically disposed work guide 33 which is fixedly secured to the bearing post 34 which 90 contains the bearings 8 and 9 for the needle shaft. Cooperating with the work guide 33 and also with the feed dog 29 is a vertical presser foot 35. This presser foot is fixedly mounted on the upper end of a lever 36 which is fulcrumed intermediate its ends on a needle shaft 11. A spring 37 is disposed between the bearing post 34 and the lower end of the lever 36 and functions to yieldably urge the presser foot 35 toward the work guide 33 and the feed dog 29.

From the foregoing, it will be apparent that the forward end of the feed bar 18 is slidably supported on the block 23 and the rear end is pivotally supported by the feed rocker or lever 17; that the feed rocker will impart backward and forward movements to the feed dog, and that the cam 25 and cam follower 24 will impart lateral reciprocations to the feed dog.

In order to oscillate the feed rocker or lever 17 and thereby impart said movements to the feed 110

dog 29, a link 38 extends longitudinally within the work arm 5 and has its rear end pivotally connected to the lower end of the feed rocker or lever 17, and the forward end of said link is pivotally connected to the lower end of a rock arm 39 which is mounted to swing about a pivot 40 and is operable by suitable connections from the main shaft of the machine.

From the foregoing, it will be observed that the lateral reciprocations to the feed dog 29 are brought about through the oscillations of the needle shaft 11; that the backward and forward movement of the feed dog is brought about by the oscillations of the feed rocker or lever 17, and that the parts are so timed whereby the components of these two movements will result in causing the feed dog to partake of an elliptical path of travel which is generally known in the art as a 4-motion travel.

Located between the vertical feed dog 29 and the free end of the work arm is a horizontal 4-motion feed dog 41 which is fixed to one end of a feed bar 42 pivoted at its other end to the upper end of the feed rocker or lever 17. The feed rocker 17 functions to impart backward and

forward movements in unison to both the vertical feed dog 29 and the horizontal feed dog 41. A 3-armed lever 43 is pivoted at its angle on a horizontal pin 44 mounted below the feed bar 42. The horizontal arm 45 of this lever is connected to the feed bar 42 by a vertical link 46, and the depending vertical arm 47 of said lever is connected to an actuating link 48 which extends along and within the work arm and is operated by the mechanism disclosed in my parent application.

It is of course to be understood that the details of structure and arrangements of parts may be variously changed and modified without departing from the spirit and scope of my invention.

I claim:—

In a sewing machine, the combination with a front vertical 4-motion feed dog, of a rear horizontal 4-motion feed dog, means including a single feed rocker for imparting back and forth movements to both dogs, and means for imparting horizontal reciprocations to the front feed dog and vertical reciprocations to the rear feed dog.
